UNITED STATES PATENT OFFICE

ANDREW M. HUNT, OF NEW YORK, N. Y.; CROCKER FIRST FEDERAL TRUST COMPANY, EXECUTOR OF SAID ANDREW M. HUNT, DECEASED, ASSIGNOR TO THE STANDARD STOKER COMPANY, INCORPORATED, A CORPORATION OF DELAWARE

FLUID COOLED DISTRIBUTING MEMBER FOR STOKERS

Application filed July 19, 1929. Serial No. 379,427.

My invention in its broader aspects relates to and has for its principal object the provision of a new, novel, and very effective cooling means for both protecting and cooling any metallic member that in use is adapted to be exposed to the intense and destructive heat of a furnace.

The present specific embodiment of the invention appertains to fuel feeding or distributing members for locomotive stokers, and has for its primary object the provision of such a member provided with a new and novel means for cooling that portion thereof that is exposed to the intense heat of the locomotive firebox.

The advantages and use of the invention will be particularly described in connection with a fuel distributor member for locomotive stokers as illustrated on the accompanying drawings, and it will be clear that its use is not necessarily restricted in its association as illustrated by the drawings, in which

Fig. 1 is a fragmentary vertical sectional view of forward or delivery portion of a stoker feeding system embodying a preferred form of the invention;

Fig. 2 is a horizontal sectional view taken on the section on the line 2-2 of Figure 1;

Fig. 3 is a perspective view of the fluid cooled feeding and distributing member shown detached from the stoker system; and

Fig. 4 is a similar view with a portion broken away to illustrate the novel chamber construction of the invention.

While the distributor member and its cooling and protective arrangement may be used with most forms of furnaces it is especially adapted for use with a locomotive firebox 10 having the backwall 11 in which there is a firing opening 12, preferably, of the conventional form used on stoker fired locomotives.

Fuel may be fed to the distributor member 13 by a suitable feeding system from a source of supply. The feeding system selected to illustrate the invention terminates in a conduit 14 fixed to the backwall, the upper end or mouth portion of this conduit opening into the lower portion of the firing opening 12.

The distributor member 13 comprises in part

a continuation of the conduit floor extending into the firing opening and somewhat beyond into the firebox, thus constituting a feeding member which is also formed with the depressions or grooves 16, 16a at its forward side portions and the abutments or ribs 17 and 17a, which together with the grooves function to direct a portion of the fuel being blown across the floor plate 15 by the blast issuing from the nozzle 18 to the rear corners of the firebox. The central portion of the floor is unobstructed to permit the delivery of fuel to the remaining portions of the firebox.

The rearward and flange portion 19 of the distributing member abuts against the rear face of the cutout 20 of the conduit, the flange being formed with threaded openings to receive headed screws 21 adapted to recesses in the bottom wall of the part 14 and whereby the member 13 is detachably fixed in place. The bottom wall of the conduit is also slotted at 22 rearward of the cutout for the distributing member to receive the nozzle 18 having forwardly projecting jet openings 23 through which a pressure fluid, preferably steam, is emitted, the fluid being supplied through supply pipes 24 and connected to the lower end of the nozzle.

It is clear from Figure 1 that with the distributor member 13 in place it extends through the lower portion of the firing opening 12, its forward end being exposed to the intense heat within the firebox. The floor 15 is spaced above the lower marginal edge 25 of the firing opening for the admission of outside air to the firebox through the passage formed beneath the floor 15. The draft of the firebox draws a current of outside air to the firebox through the entrance 26 beneath the floor, the air in its passage through the firing opening beneath the plate impinging against the distributing member to effect a more or less cooling of the part to protect it from the intense heat and burning away of that portion of the member exposed to the fire.

The construction so far described is widely used in stoker devices, the use of which in actual service has demonstrated that the

mere provision of a passage for entrance of air beneath the distributing member, while being better than no passage at all, it does not serve to sufficiently protect the distributor member to prevent rapid deterioration and burning away of that portion exposed to the heat rays of the fire and in many instances the flame of the fire.

This invention is directed to what is believed to be a novel and what in actual practice has proven to be a very effective cooling and protective means for use with any part or member that may be exposed to the heat or flame of the fire within a furnace and in practice it has particularly proven its utility for use in connection with the distributing member 13 of the form described.

As will be seen from Figure 3 and later referring to Figure 1, the fuel distributing member 13 and its cooling and protective means is a unitary structure, the plate 15 having formed therewith at its under side a chamber 30, the walls of which extend from the plate a distance sufficient to provide a suitable space 31 opening unrestrictedly at the rearward end of the casing for the admission of air when the distributing member is in place as shown in Figure 1.

A plurality of perforations, preferably, closely spaced holes 32 are provided in the bottom, forward, and side walls of the chamber for the emission of the cooling fluid from the space 31 to the firebox. The ribs as at 33 are provided for the purpose of adding strength to the member 13 and to eliminate a tendency of warping or bending of its plate portion 15.

The bottom and side walls of the chamber extend rearwardly from the extreme front end of the plate 15 to a point short of the flange 19. When the distributing member is in position the walls of the chamber meet the lower marginal edge of the firing opening to form a closure between the interior of the firebox and the entrance 26 beneath the plate 15. The open end of the chamber is then in direct communication with and to receive air or other cooling fluid from the entrance 26 which permits the admission of the cooling fluid into that portion of the firing opening beneath the distributing member.

An important feature of the invention is the particular way in which the cooling fluid is drawn into the firebox and brought into contact with the portion of the distributing member that is exposed to the fire. This is done by the draft in the firebox creating a suction in the space 31 and the entrance 26 through the perforations of the chamber walls, the air or other cooling fluid by the reason of the suction created being rapidly drawn at a suitable velocity through the chamber and its perforations into the firebox.

From the foregoing description and the

drawings, it will be observed that the portion of the distributor member over the surface of which fuel is distributed is protected from the heat of the fire by a spaced chamber the walls of which receive full impingement of heat radiation and is cooled by the outside air, or other cooling fluid which passes through the space 31, emitting therefrom and entering the firebox through the perforation, which, by reason of the closely spaced area exposed to cooling action of the entering air maintains the distributor member below destructive temperature. The close spacing of the perforations provides that no point of the structure is far removed from a cooling surface and thus the path of heat flow is short. To obtain the most effective results it is preferred that the wall thickness of the perforated chamber be equal to or greater than one half of the radius of the circular section of the perforation for then the net effect of the perforations will be to increase the cooling area of the chamber.

The chamber is shown as being formed integral with the plate portion 15 of the distributing member and this is the preferred construction to insure conduction of the heat flow and the cooling action of the cooling fluid from one portion of the distributor member to the other, but it is plain that the chamber may be formed separable from the distributing member if the furnace temperature is such as to permit some loss of effectiveness of the cooling arrangement without destroying the utilities of the invention.

It will be apparent that various other constructional changes may be made without departing from the spirit of the invention and that the novel cooling arrangement may be used for cooling and protecting any part that in use may be exposed to the heat rays or the flow of the fire in a locomotive firebox or in other like furnaces.

I claim:

1. In combination with a firebox having a backwall with a firing opening therein, a distributing table extending through the lower portion of said opening into the firebox above the level of the fire, said table spaced above the lower marginal edge of said opening to provide an entrance below for admission of air from without the firebox into that portion of the firing opening beneath said table, said table comprising a table top arranged to permit fuel to pass thereover for distribution, forward, side and bottom walls forming in conjunction with said table top a chamber on the underside thereof, said chamber open at its rearward end in communication with said entrance for the admission of air, each of said walls having a plurality of perforations that are spaced apart from said table top for the emission of air from the chamber into the firebox, the draft within the firebox acting to draw air from without the firebox through the chamber and its perforations, whereby the

distributing table is protected from the intense heat of the firebox by reason of the cooling action of the entering air on the surfaces of the table top and chamber walls.

- 5 2. A fuel distributing table for stokers comprising a table top arranged to permit fuel to pass thereover for distribution, a forward wall and side walls depending from said table top, a bottom wall spaced apart from 10 said table top and forming in conjunction with said table top, forward and side walls a chamber on the underside of said table top, said side walls being provided with a plurality of perforations, and said forward wall 15 having a plurality of perforations spaced in a row extending substantially the full length of the wall and said bottom wall having a plurality of perforations therein spaced in a plurality of longitudinal and transverse rows.
- 20 3. A fuel distributing table for stokers comprising a table top arranged to permit fuel to pass thereover for distribution, forward, side and bottom walls forming in conjunction with said table top a chamber, said 25 chamber opening at its rearward end for admission of a cooling fluid for protecting that portion of the distributing table that when in use is exposed to the intense heat of a firebox, said forward and bottom walls being 30 provided with a plurality of closely spaced perforations for the emission of the cooling fluid from said chamber, the perforations in said forward wall spaced in a row extending substantially the full length of the wall and 35 the perforations in said bottom wall being spaced in a plurality of longitudinal and transverse rows.
4. A fuel distributing table for stokers comprising a table top arranged to permit fuel to pass thereover for distribution, forward, side and bottom walls forming in conjunction with said table top a chamber, said 40 chamber opening at its rearward end for admission of a cooling fluid for protecting that portion of the distributing table that when in use is exposed to the intense heat of a firebox, said forward and bottom walls being 45 provided with a plurality of closely spaced perforations for the emission of the cooling fluid from said chamber, the perforations in said forward wall spaced in a plurality of transverse and vertical rows and the perforations in said bottom wall being spaced in a plurality of transverse and longitudinal 50 rows.
- 55 5. A metallic fuel distributing table for use with a furnace in a position therewith above the level of the fire and adapted to be exposed to the intense heat within the firebox, said distributing table comprising a 60 plate portion arranged to permit fuel to pass thereover for distribution, forward, side and bottom walls formed integral with said plate portion and forming in conjunction therewith a chamber, said chamber opening at its 65 rearward end for admission of a cooling fluid for protecting that portion of the distributing table adapted to receive full impingement of the heat rays of the fire directed on said table, said forward, side and bottom 70 walls being provided with a plurality of closely spaced openings of substantially uniform diameter for the emission of fluid from said chamber, the perforations in said forward wall spaced in a transverse row extending substantially the full length of the wall and the perforations in said bottom wall being spaced in a plurality of longitudinal and transverse rows.
- 75 6. A metallic fuel distributing table for use with a furnace in a position therewith above the level of the fire and adapted to be exposed to the intense heat within the firebox, said distributing table comprising a 80 plate portion arranged to permit fuel to pass thereover for distribution, forward, side and bottom walls formed integral with said plate portion and forming in conjunction therewith a chamber, said chamber opening at its rearward end for admission of a cooling fluid 85 for protecting that portion of the distributing table adapted to receive full impingement of the heat rays of the fire directed on said table, said forward, side and bottom walls being provided with a plurality of closely spaced openings of substantially uniform diameter for the emission of fluid from said chamber, the thickness of the perforated walls of said chamber being equal to or greater than one half of the radius of the circular 90 section of said substantially uniform diameter openings, said openings in the forward wall spaced in a transverse row extending substantially the full length of the wall and the openings in said bottom wall being spaced in a plurality of longitudinal and transverse rows.
- 95 100 7. In combination with a firebox having a backwall with a firing opening therein, a fuel distributing table extending through the lower portion of said opening into the firebox above the level of the fire, said table spaced above the lower marginal edge of said opening to provide an entrance below for admission of air from without the firebox into 110 that portion of the opening beneath said table, said table comprising a table top arranged to permit fuel to pass thereover for distribution, forward, side and bottom walls forming in conjunction with said table top 115 a chamber on the underside thereof, the walls of said chamber arranged to form with the lower marginal edge of the firing opening a closure between the interior of the firebox and the entrance beneath the plate for the admission of air, said walls directing the entering air against the underside of said plate and having in each a plurality of closely spaced perforations forward of their juncture with the marginal edge of said firing opening,

the draft within the firebox acting to draw air from said entrance through the chamber and its perforations into the firebox, whereby the distributing table is protected from 5 the intense heat of the fire by reason of the cooling action of the entering air on the surface of the table and the walls of the chamber.

In testimony whereof I affix my signature.
